(57) CLAIM

The ornamental design for a coin purse, as shown and described.

DESCRIPTION

FIG. 1 is a perspective view of the coin purse;

FIG. 2 is a top view thereof;

FIG. 3 is a right side view of the coin purse; the left side being a mirror image thereof;

FIG. 4 is a top view thereof;

FIG. 5 is a rear view thereof; and,

FIG. 6 is a bottom view thereof.

The broken lines shown in the drawings illustrate portions of the coin purse that form no part of the claimed design.
